GEORGE P. FULLER, OF PHILADELPHIA, PENNSYLVANIA.

Letters Patent No. 95,219, dated September 28, 1869.

IMPROVED MODE OF HANGING WINDOW-SHADES.

The Schedule referred to in these Letters Patent and making part of the same.

To all whom it may concern:

Be it known that I, GEORGE P. FULLER, of the city of Philadelphia, and State of Pennsylvania, have invented a new and improved Mode of Hanging Window-Shades in relation to ventilation; and I do hereby declare that the following is a full and exact description thereof, reference being had to the accompanying drawings, and to the letters of reference marked thereon.

The object of this invention is the lowering of the upper end of the shade, as the upper sash is moved downward, to make a free passage for air above the sash, without changing the height of the lower end of the shade. This I accomplish by confining the slat to which the upper end of the shade is attached to brackets, that are connected with the sash, and encircling the shade with a band, at a short distance from each vertical edge; said bands being connected at one end with the sash, and at their other end with the slat, and being hung in staples, in connection with the window-frame head, in which their middle portions are caused to slide as they move upward, as the ends move downward with the sash and said slat. This upward motion causes a roller, to which the lower end of the shade is attached, to revolve, and thereby wind up the shade at its lower end, at the same rate as the upper end is lowered.

The construction and arrangement of the device will be understood by the following description.

In the accompanying drawings, which make a part of this specification—

Figure 1 is a face view of a window-frame and sash with the improved shade-attachments.

Figure 2 is a vertical section at the dotted line *a b* of fig. 1.

Figure 3 is an isometrical view of one of the brackets, *b*.

Like letters in all the figures indicate the same parts.

A is a window-frame.

B is the lower, and *C*, the upper sash.

The upper end of the shade *D* is attached to the slat *a*, and the latter confined to the brackets *b b*, which project horizontally from the sash.

The lower end of the shade is confined to the roller *E*.

F F are bands, which pass through the staples, *c c* and *c c*, in the head-piece *d* of the window-frame, and encircle the shade *D*.

The ends of the bands are confined to eyes, *e*, in the upper rail of the sash *C* and the slat *a*.

The bands are separated in the middle, to provide for varying their length, to regulate the height of the lower end of the shade, being connected by means of the buckles *f* and eyelets *g*.

The operation is as follows:

As the sash *C* is moved downward, for ventilating the room, the inner ends of the bands *b* being connected with it, and the slat *a* attached thereto, the inner parts of the bands move downward accordingly, causing the outer parts to move upward and slide through the staples *c c*, and thus causing the roller *E* to turn and wind up the shade *D* at its lower end, at the same rate as it is lowered by the downward movement of the sash *C*. Thus the upper end of the shade is lowered with the sash, to favor the ventilation, and the height of its lower end preserved by the same movement.

The buckles and eyelets may be dispensed with, to cheapen the device, the bands being tied in bow-knots, or otherwise connected.

Instead of having two bands, in some cases one may be found sufficient, especially for narrow shades.

In some cases, especially in the use of heavy shades, pulleys should take the place of the staples *c*.

What I claim as my invention, and desire to secure by Letters Patent, is—

The combination and arrangement of the bands *F F*, staples *c*, brackets *b*, and slat *a*, with the shade *D*, sash *C*, and frame *A*, substantially in the manner above described.

In testimony that the above is my invention, I have hereunto set my hand and affixed my seal, this 22d day of July, 1869.

GEORGE P. FULLER. [L. s.]
